POLISH ROD CLAMP

**Fred D. Stanley, Coffeyville, Kans., assignor to
The Oil Country Specialties Manufacturing
Company, Coffeyville, Kans., a corporation of
Kansas**

Application October 20, 1939, Serial No. 300,303

15 Claims. (Cl. 24—248)

This invention relates to a polish rod clamp for use in connection with the polish rod of oil well pumping units.

In pumping mechanism for oil wells, the line of sucker rods terminates at its upper end in a length of rod, having a rather high degree of polish, which oscillates back and forth through the stuffing box at the top of the well, and which is called the polish rod. In order to impart the reciprocatory motion to the string of sucker rods, the polish rod is connected through a suitable clamp and connecting linkage to the beam of the pumping mechanism.

Such a polish rod clamp must effectively engage the rod, and thereby provide a firm abutment against which the pulling force of the pumping mechanism may be applied and transmitted to the sucker rods.

The object of the present invention, generally stated, is to provide a polish rod clamp which will positively engage a polish rod, and yet be capable of ready release and removal.

Another object of the invention is to provide a polish rod clamp which is simple to manufacture and install, but in which the various parts are connected together so that they will not become displaced when the clamp is not engaged.

Other objects of the invention will become apparent to those skilled in the art when the following description is read in connection with the accompanying drawing, in which:

Figure 1 is a front view of a polish rod provided with a clamp constructed in accordance with the present invention, together with the lift mechanism therefor.

Figure 2 is a plan view of a polish rod clamp constructed in accordance with the present invention, in open position.

Figure 3 is a plan view of the polish rod clamp shown in Figure 2, but in closed position.

Figure 4 is a view in side elevation of the polish rod clamp shown in Figure 1.

The present invention contemplates a polish rod clamp in which the polish rod is circumferentially engaged by the clamp substantially throughout its circumference. A particular feature of the invention resides in the provision of gripping members in sets of three, each provided with polish rod engaging notches formed on substantially the same radius as that of the polish rod, the respective notches embracing nearly one hundred eighty degrees of the polish rod circumference. The gripping members are hingedly mounted with respect to each other, so

that the notches overlap when the clamp is closed.

In the embodiment illustrated in the drawing, a pair of clamp members is arranged so that the individual members oppose each other. Both members are mounted upon a third member, and each of the three is provided with the polish rod engaging notch above referred to. Any suitable means may be provided for forcing the pair of opposed members together and holding them in position so that they will grip the polish rod not only against each other, but against the third member.

Referring now particularly to the drawing for an illustrative embodiment of the present invention, the clamp is applied to a polish rod 1 so as to provide an abutment against which a lifting force may be applied. In accordance with the usual practice, the lifting force is applied through a suitable clamp supporting plate 2, which is connected by means of hangers 3 to the beam of the pumping mechanism.

The clamp of the present invention consists of a supporting member 4, having a central notch 5, formed on the same radius as that of polish rod 1. The notch 5 has a circumferential extent of nearly one hundred eighty degrees in the embodiment shown in the drawing, the extent thereof being approximately one hundred fifty degrees. Hingedly mounted upon supporting member 4, on opposite sides of notch 5, is a pair of clamping members 6 and 7. Each of clamping members 6 and 7 is likewise provided with a polish rod engaging notch 8 and 9, formed on the same radius as that of polish rod 1, having an extent of nearly one hundred eighty degrees. Clamping member 6 is connected to supporting member 4 through a hinge pin 10, and correspondingly clamping member 7 is connected to the opposite end of supporting member 4 through the hinge pin 11.

Another pair of clamping members 16 and 17 is similarly mounted upon the lower side of supporting member 4. Clamping members 16 and 17 are provided with polish rod engaging notches identical with notches 8 and 9 in clamping members 6 and 7.

In order to force the clamping members into firm engagement with the polish rod, any suitable means for holding the clamping members together may be provided. In the embodiment illustrated, a bolt 12 extends between the pair of clamping members 6—7, and the pair of clamping members 16—17 parallel to supporting member 4. In order to accommodate the head of bolt

12, clamping members 7 and 17 may be provided with shoulders 13 as clearly shown in Figure 1, so that the head of clamping bolt 12 is recessed so as to be substantially flush with the edge surfaces of the clamping members 7 and 17.

While in the accompanying drawing the polish rod clamp of the present invention is shown as consisting of four supporting members, 4, 14, 24, and 34, each of which is identical with member 4 hereinbefore described in detail; and consisting of five pairs of clamping members 6-7, 16-17, 26-27, 36-37, and 46-47, it will be understood that the clamp may be enlarged by the addition of additional sets of supporting and clamping members; or may be reduced in size by eliminating some of the same, down to a minimum of two pairs of clamping members and one supporting member.

In order to facilitate the manufacture of the clamping device of the present invention, the clamping members 6, 7, 26, 27, 46 and 47, may be identically formed; as it will be observed that clamping member 6 is identical with clamping member 7, but is in inverted position, so that the polish rod engaging notches face each other, and so that shoulders 13 face away from each other diagonally. Likewise members 16, 17, 36 and 37 are identical. The arrangement of parts so that the clamping members of each pair are identical is a great convenience in manufacturing, as well as in maintenance, because it is not necessary to provide the user with a large supply of replacement parts, in view of the fact that the clamping members of each pair, regardless of how many there may be or whether they are right-hand or left-hand members, are identical, and the alternate pairs are also identical.

In a polish rod clamp having more than two sets of clamping members such as 6-7, 16-17, it is desirable to provide more than one clamping means such as bolt 12. Accordingly, in the embodiment illustrated, there is provided four clamping bolts, 12, 22, 32 and 42, which it will be observed extend in alternately opposite directions. With all of the clamping members identically formed, the position of shoulders 13 on each alternate pair of clamping members will be opposed; and consequently alternate positioning of the clamping bolts is required. This, however, is an added convenience, because greater space for manipulating the nuts on the clamping bolts is thereby provided.

In order to facilitate manipulation of the device, all of the clamping members on one side of the polish rod may be pinned together, as for example through the medium of a pin 18 extending through suitably aligned holes in the respective clamping members 6, 16, 26, 36, and 46. Likewise, a pin 19 extends through and connects together clamping members 7, 17, 27, 37, and 47. Pins 18 and 19 perform the additional function, however, of locating bolts 12, 22, 32 and 42 in position between the respective pairs of clamping members. Pin 18 positions the clamping bolts outwardly from supporting member 4, while pin 19, being on the outside of bolt 12, prevents their becoming detached from the clamp except when the nut is entirely removed therefrom.

In order to further facilitate the application of the polish rod clamp, suitable handles may be provided on any one or more of the clamping members. For example, handle 20 may be connected between clamping member 6 and clamping member 36; and a corresponding handle 21 may be connected between clamping member 7 and

clamping member 37. This provides an easy grip whereby when it is desired to open or close the clamp, the handles may be gripped in the hands and manipulated in the proper direction.

From the foregoing description it is believed that the mode of operation of the device will be apparent to those skilled in the art, and that its advantages will be manifest. It is pointed out, however, that the invention is not limited to the particular number of pairs of clamping members which are shown in the embodiment of the drawing, but that the clamp may be enlarged or diminished in accordance with the requirements of the particular mechanism upon which it is being employed. Infinite number of pairs of clamping members may be added to the device shown in the drawing, with supporting members corresponding to member 4 intervening each pair; and likewise the number of pairs of clamping members may be decreased to a minimum of two pairs, with one supporting member 4 intervening. In any event, in order to assure adequate clamping, the same number of clamping bolts 12 should be employed as there are supporting members 4.

While it is realized that many modifications and variations of the device will present themselves to those skilled in the art, it is to be distinctly understood that such modifications and variations, and the use of such individual features and combinations of features as do not depart from the spirit of this invention are, although not specifically described herein, contemplated by and within the scope of the appended claims.

Having thus described the invention, what is claimed is:

1. A polish rod clamp comprising a member having a notched part shaped to embrace and engage a polish rod, a plurality of other members hinged at the ends of said first member but disaligned therefrom, and each having notched parts shaped to embrace and engage a polish rod, and means for drawing said members together to clamp the polish rod in said notched parts of all said members.

2. A polish rod clamp comprising a member having an arcuate notch arranged to engage a polish rod, a plurality of other members pivoted to said member and each having arcuate notches to engage the polish rod, and means for clamping said members together with the polish rod engaging portions of the arcuate notches overlapping.

3. A polish rod clamp comprising a series of members having arcuate notches, members pivoted to each end of the first mentioned members and interposing the same, and means for clamping said last mentioned members together to force a polish rod into engagement with said arcuate notches.

4. A polish rod clamp comprising a member having a part arranged to engage a polish rod, a pair of clamping members hinged on top of said first mentioned member, another pair of clamping members hinged on the bottom of said first mentioned member, said clamping members each having parts to engage the polish rod at points axially and circumferentially displaced from the point of engagement by said first mentioned member, and means for drawing said clamping members together.

5. A polish rod clamp comprising a member having a part arranged to engage a polish rod, a pair of clamping members hinged on top of said first mentioned member, another pair of clamping members hinged on the bottom of said first mentioned member, said clamping members each

having parts to engage the polish rod at points axially and circumferentially displaced from the point of engagement by said first mentioned member, and means for concurrently drawing both pairs of said clamping members together.

6. A polish rod clamp comprising a member having a part arranged to engage a polish rod, a pair of clamping members hinged on top of said first mentioned member, another pair of clamping members hinged on the bottom of said first mentioned member, said clamping members each having parts to engage the polish rod at points axially and circumferentially displaced from the point of engagement by said first mentioned member, and a bolt extending parallel to said first mentioned member between the respective pairs of clamping members for drawing the latter together.

7. A polish rod clamp comprising a member having a part arranged to engage a polish rod, a pair of clamping members hinged on top of said first mentioned member, another pair of clamping members hinged on the bottom of said first mentioned member, said clamping members each having parts to engage the polish rod at points axially and circumferentially displaced from the point of engagement by said first mentioned member, a bolt extending parallel to said first mentioned member between the respective pairs of clamping members for drawing the latter together, and a loose connection between said bolt and one of said clamping members.

8. A polish rod clamp comprising, a pair of clamping members having opposed polish rod gripping notches, a supporting member beneath said pair of clamping members, another pair of gripping members disposed beneath said supporting member, a pair of hinge pins each connecting one of each pair of clamping members to the ends of said supporting member, and means for drawing said clamping members together.

9. A polish rod clamp comprising, a pair of clamping members having opposed polish rod gripping notches, a supporting member beneath said pair of clamping members, another pair of gripping members disposed beneath said supporting member, a pair of hinge pins each connecting one of each pair of clamping members to the ends of said supporting member, a pin extending through the clamping members connected with one hinge pin for maintaining the same in alignment, and means for drawing said clamping members together.

10. A polish rod clamp comprising, a pair of clamping members having opposed polish rod gripping notches, a supporting member beneath said pair of clamping members, said supporting member having a central notch for engaging a polish rod, another pair of clamping members beneath the supporting member, one clamping member of each pair being hinged at one side of

the notch in the supporting member and the other on the opposite side thereof, the notches in the clamping members overlapping the notch in the supporting member, and means for drawing said clamping members together.

5 11. A polish rod clamp comprising a supporting member having an arcuate notch of nearly 180° on substantially the same radius as the polish rod, a pair of clamping members each having an arcuate notch of nearly 180° on the same radius as the polish rod, means for hingedly mounting said clamping members on said supporting member so that the arcs of the respective notches may be circumferentially aligned, and means for drawing said clamping members together.

10 12. A polish rod clamp comprising, a pair of clamping members having opposed polish rod gripping notches, a supporting member beneath said pair of clamping members, another pair of gripping members disposed beneath said supporting member, a pair of hinge pins each connecting one of each pair of clamping members to the ends of said supporting member, a pin extending through the clamping members connected with one hinge pin for maintaining the same in alignment, handles extending outwardly from oppositely disposed said clamping members, and means for drawing said clamping members together.

15 13. A polish rod clamp comprising, a supporting member, and a plurality of identical clamping members hinged to said supporting member in spaced relation, each of said clamping members having a polish rod engaging notch, said individual clamping members being mounted so that the notch thereof opposes the notch in the companion clamping member of the identical pair.

20 14. A polish rod clamp comprising a supporting member, and a plurality of identical clamping members hinged to said supporting member in spaced relation, each of said clamping members having a polish rod engaging notch and a recessed shoulder along an edge thereof opposite said notch, said individual clamping members being mounted so that the notch thereof opposes the notch in the companion clamping member of the identical pair.

25 15. A polish rod clamp comprising, a pair of clamping members having opposed polish rod gripping notches, a supporting member beneath said pair of clamping members, another pair of gripping members disposed beneath said supporting member, a pair of axially extending hinge pins each connecting one of each pair of clamping members to the ends of said supporting member, and a clamping bolt extending crosswise at the ends of said clamping members opposite said hinge pins for drawing together the clamping members of the pairs above and below the clamping bolt.

FRED D. STANLEY.
